UNITED STATES PATENT OFFICE.

FRANK L. IRWIN AND JOHN E. TESSEYMAN, OF COLUMBUS, OHIO, ASSIGNEES TO THE
RALSTON STEEL CAR COMPANY, OF COLUMBUS, OHIO, A CORPORATION OF OHIO.

HOPPER-CAR.

1,075,572.

Specification of Letters Patent. Patented Oct. 14, 1913.

Application filed May 26, 1911. Serial No. 629,711.

To all whom it may concern:

Be it known that we, FRANK L. IRWIN and JOHN E. TESSEYMAN, citizens of the United States, residing at Columbus, in the 5 county of Franklin and State of Ohio, have invented certain new and useful Improvements in Hopper-Cars, of which the following is a specification.

Our invention relates to improvements 10 in hopper cars and has especial reference to the construction of a cross hood between the hoppers and the manner of securing the same to the sides of the car and of reinforcing the said hood, and strengthening 15 the car construction at this point.

The form of cross hood especially included herein comprises sloping side sheets which do not meet at their upper ends and an apex or ridge member applied to the 20 said upper ends and formed preferably of a single piece of metal pressed to form a vertical fold along the ridge thereof and having sloping sides which overlie and are secured to the upper ends of the side sheets 25 of the cross hood. Another feature of the cross hood construction is a bracing diaphragm disposed between the sloping sides of the cross hood and extending from the center sill to the outer end of the cross hood 30 and being connected with an angle brace which extends across the cross hood and is secured to the sloping side sheets which will appear in the more detailed description hereinafter.

35 In the drawings which are hereto attached and hereby made a part of this specification, Figure 1 is a vertical longitudinal section through one end of the car between the center sill and the side of the 40 car; Fig. 2 is a vertical transverse section through the car approximately on the line A—A of Fig. 1 between the end slope sheets and cross hood; Fig. 3 is a side view of the reinforcing member applied to the car at 45 each side of the center girder and extending longitudinally inside of the hood. Fig. 4 is a top view of the cross hood, illustrating the application thereof to the center girder construction. Fig. 5 shows in detail the 50 construction of the reinforcing member and its connection with the other features of the car construction, and is a section taken along the line M—M of Fig. 6. Fig. 6 is an enlarged detail of the cross hood in vertical transverse section, omitting the center

girder construction and means of attachment thereto.

In the drawings, 1 is the center girder construction formed, in this instance, of the parallel channels with their flanges inwardly disposed; 2 are the end slope sheets; 3 is the side of the car; 4 is the center sill hood traversing the car longitudinally and having its lower edges flanged at 5 and 6 and applied to the vertical webs of the center sill channels and secured thereto at 7 and 8. At one end the center sill hood is secured to the end slope sheets at 9 generally in a well known manner not illustrated, and at the other end flanges 10 and 11 are 70 formed on the center sill hood and applied to the cross hood, being secured thereto at 12 and 13.

The cross hood is formed of the oppositely inclined sheets 14 and 15 having at 75 their lower edges respectively the angle braces 16 and 17 riveted thereto at 18 and 19, whereby the lower edges of said sheets are reinforced. Angles as shown at 20 are applied to the center sill and secured thereto 80 by rivets as shown at 21, and are also secured to the inner end of the cross hood sheets 14 and 15 by rivets as appears at 22. It is seen that the upper ends of the sheets 14 and 15 do not meet, and we provide a 85 ridge or cover member which is formed of the sheets 25 and 26, having the diverging sides or flanges which overlap respectively the upper ends of the inclined sides 14 and 15 of the cross hood and are secured thereto 90 by rivets as appears at 27 and 28. Sheets 25 and 26 have upwardly extending flanges 23 and 24, projecting above the center sill cross hood, and are secured together by the rivets 29. This construction is very strong 95 and provides reinforcement for the cross hood at points where great strength is required.

At the sides of the car are provided inside side stakes formed of the angles 24^a and 24^b 100 which have wide inwardly projecting flanges as appears at 24^c, having their lower ends inclined outwardly as appears at 24^d and secured by rivets at 24^e to the flanges 23 and 24, thereby securing the cross hood construction to the sides of the car. It will be understood that a similar construction is provided at the opposite side of the car.

An outside side stake is shown at 32, the flanges 31 of which are riveted as at 30 to 110

the side 3 of the car and the flanges 24^a and 24^b of the inside side stake. An angle 33 is secured along the lower edge of the side of the car by means of the rivets 34 which pass 5 through the upturned flange of said angle and the side of the car and the flange of the outside side stake 32. The angle 33 is utilized in connection with the bracing of the cross hood as appears hereinafter. At 35 the 10 sheet 26 is flanged and is applied to the side of the car.

A bracing angle 36 bent outwardly at its ends 37 and 38 is secured to the cross hood sheets 14 and 15 and abuts at its ends against 15 a flange of the angles 16, 17, whereby a rigid brace is formed transversely of the cross hood. We also provide a reinforcing diaphragm 39 shown especially in Figs. 3 and 5, which is flanged along the edges 42 and 43, 20 and secured through the flange 40 by rivets 41 to the center sill and by rivets 46 to a tension member 44 which overlies the center sill and is secured thereto at 45, and by rivets 49 diaphragm 39 is secured to a compression member 47 underlying the center sill and being secured thereto at 48. An angle member 50 riveted at 51 to the center sill is secured at 52 to the diaphragm 39. At 53 is provided an angle member secured to the 25 diaphragm 39 at 54 and to the side of the car at 55. The flange 56 of the side angle 33 arranged on the lower edge of the side 3 of the car is secured at 57 to the compression member 47, and rivet 58 secures together the 30 bracing member 36, the compression member 47 and the flange 43 on the diaphragm 39, whereby a very strong support is secured for the cross hood construction, binding the same to the diaphragm and to the side of the 35 car, such that the stresses set up in the use and operation of the car will be absorbed to a very great extent; and since the hood and the related parts are secured to each other and to the sides of the car and to the center 40 sill, the construction has great strength.

The features of our invention herein are seen to be therefore a cross hood formed of sloping side sheets connected at their upper ends by a ridge member with diverging sides, means for securing the ridge member to the 50 sides of the car, and means for securing the side sheets to the center sill and to the sides of the car, and the bracing construction provided within the hood both transversely and longitudinally thereof. 55

What we claim is:

1. In a car having a center sill, a cross hood formed of sloping side sheets, a brace member within said hood secured at its ends to said sloping side sheets, and a reinforcing 60 diaphragm within said hood secured to the center sill, the brace member and the side of the car, and a tension member applied to the center sill and said diaphragm.

2. In a car having a center sill and cross 65 hood formed of sloping side sheets spaced apart at their upper edges, a brace member placed transversely in said hood and applied at its ends to said sheets, and a reinforcing diaphragm within said hood superposed 70 upon said brace member and secured thereto and to said center sill.

3. In a car having a center sill, a cross hood formed of sloping side sheets spaced apart at their upper edges, a transverse 75 brace member in said hood having its ends downwardly divergent and applied to said sheets near their lower edges, and a reinforcing diaphragm arranged longitudinally of said hood and bearing upon said brace member and being secured thereto and to said center sill. 80

In testimony whereof we affix our signatures in the presence of two witnesses.

FRANK L. IRWIN.
JOHN E. TESSEYMAN.
